UNITED STATES PATENT OFFICE

106,101

DESIGN FOR A SLIP

Sam Landau, New York, N. Y.

Application July 28, 1937, Serial No. 70,699

Term of patent 3½ years

To all whom it may concern:

Be it known that I, Sam Landau, a citizen of the United States of America, residing in Manhattan, county of New York, and State of New York, have invented a new, original, and ornamental Design for a Slip, of which the following is a specification, reference being had to the accompanying drawing, forming part thereof, wherein,

The slip of this application is characterized by the inclusion of lace insertion arranged in chevron like formation, as shown.

I claim:

The ornamental design for a slip, substantially as shown and described.

SAM LANDAU.
